UNITED STATES PATENT OFFICE

2,619,231

UNIVERSAL OIL FILTER MOUNTING FOR
HYDRAULIC MACHINE TOOLSOlney J. Abbott, Jr., Detroit, Mich., assignor to
Colonial Broach Company, Township of Warren,
Mich., a corporation of Delaware

Application June 19, 1947, Serial No. 755,804

2 Claims. (Cl. 210—150)

1

This invention relates to hydraulic machines and more particularly to a universal oil filter mounting for such machines.

It is an object of this invention to provide a universal mounting for the oil filters employed in hydraulically operated machines, which mounting is adapted for use on various sizes and types of machines, regardless of the amount of oil which must be pumped in order to operate the machines.

It is a further object of this invention to provide a universal oil filter mounting of the aforementioned type which is connected to the oil reservoir of a hydraulic machine, and which has a container portion which extends outwardly beyond the outline of the machine so as to provide an exteriorly accessible reservoir portion having a covered opening therein which permits the oil filters of the machine to be viewed and removed, from the exterior of the machine.

It is a further object of the invention to provide an oil filter mounting of the aforementioned type, having a manifold therein, which is communicable with the oil reservoir through one or more oil filters, and which is connectible to one or more oil pumps of the machine, on which it is mounted.

These and other objects of this invention will become apparent from the following detailed description taken in conjunction with the accompanying drawings in which:

Figure 1 is a partially broken away side view of the lower portion of a hydraulic machine embodying the features of this invention;

Fig. 2 is an enlarged cross sectional view of an oil filter taken along the line 2—2 of Fig. 1;

Fig. 3 is a sectional view of the structure illustrated in Fig. 1 taken along the line 3—3 thereof; and

Fig. 4 is an end elevational view of the structure illustrated in Fig. 1 taken in the direction of the arrow 4 thereof.

Referring now to the drawings, it will be seen that the frame 5, of any suitable hydraulically operated machine, includes a base 7, a portion of which forms a fluid reservoir 9 for the machine. Above the fluid reservoir 9, and mounted on a plate 11, forming the upper wall of the base 7, is an electric motor 13 which is drivingly connected, in a conventional manner, to a fluid pump 15. It will be understood that, as is common, additional pumps may be employed, either driven by the motor 13 or separate motors.

Connected to the outside wall 17 of the machine frame 5, is a generally box-shaped container element 19 providing a portion of a com-

2

plete container or container assembly, as will hereinafter appear. The inner wall 21 of the container element 19 is formed with a large rectangular opening 22 therein, and with an outturned marginal flange 23. The flange 23 abuts a complementary flange portion 25 of the outside wall 17 of the machine, which defines a rectangular opening 26 therein. The opening 26 communicates with the fluid reservoir 9, in the base 7. A gasket 27 is disposed between the adjacent faces of the container flange 23 and base flange 25, and cap screws 29 secure the flanges in sealing relation.

A relatively large rectangular shaped opening 30 is provided in the top wall 31 of the container element or portion 19, and a cover plate 32 is provided for covering the opening 30. Ears 33 are formed at the opposite ends of the front edge of the cover 32, so as to be disposed adjacent to an upstanding flange 35 on each side wall 37 of the container 19. A pivot pin 39 hingedly connects each of the ears 33 to its adjacent flange 35, so that the cover plate 32 is hingedly mounted on the upper end of the container element or portion 19, and covers the opening 30, when closed. A handle 43 is provided on the extreme rear end of the cover plate 31 to facilitate raising of the same.

A generally rectangular shaped manifold casting on container portion 45 is disposed within the fluid reservoir 9 and has an outturned peripheral flange 47 formed around the rear edge thereof. The flange 47 abuts the inner wall 21 of the container element or portion 19, and is secured thereto by cap screws 49 so as to form the complete container or container unit with a portion disposed within the reservoir and a portion disposed exteriorly of the outline of the machine. An opening 51 provided in a bottom wall portion 53 of the manifold communicates with the fluid reservoir 9 and with the interior of the container 19. A cored chamber 55 provided in the manifold is defined by the manifold inner wall 57, a top wall 59, an outer wall 61 and suitable end walls. The manifold outer wall 61, which separates the manifold chamber 55 from the interior of the container element or portion 19, is provided, adjacent its lower edge, with three transversely spaced, tapped apertures 65, and with two tapped apertures 67, disposed above the apertures 65. The apertures 67 and 65 connect the interior of the manifold chamber 55 with the interior of the container element or portion 19 so that fluid may flow through the opening into the manifold chamber.

Oil filters 71, are illustrated in the drawings,

as being threaded into the apertures 65. The oil filters are of a conventional type having a coarse cylindrically shaped outer screen 73 (Fig. 2) and a fine inner screen 75, which is star shaped in cross section. End plates 71 and 79 are provided at the opposite ends of the screens which are connected by screws 81. A male coupling member 83 extends forwardly from the front end plate 79 of each filter and is threaded into one of the openings 65 to thereby connect each filter in the wall 61. While three filters 71 are illustrated as being connected in the openings 65, with the opening 67 plugged by means of plugs 85, it will be appreciated that any desired number, up to five, may be employed, depending on the flow requirements of the machine, and that the remaining apertures 67 or 65 must be plugged. In this way any desired number of the openings may connect the interior of the chamber 19 with the manifold chamber 55 through the filter, or filters, 71, depending upon the machine on which the mechanism is mounted, and the amount of oil which is pumped from the reservoir.

The upper wall 59 of the manifold chamber 55 is formed with three transversely spaced bosses 87, each of which has a tapped opening 89 therethrough. One of the openings 89 is illustrated in the drawings as being connected to the pump 15 by means of a conduit 91, while the other two openings are plugged by plugs 92. However, more than one pump may be used, and each pump which is used is connected by a conduit 91 and flare nut 92 in one of the openings 89. The number and capacity of the pumps used depends upon the requirements of the machine, and the number of filters will vary correspondingly. Accordingly the unit herein described provides a universal mounting and oil pump intake manifold.

This construction will permit the filters 71 to be viewed through the container opening 30 and the hydraulic fluid, and if the filters are clogged or otherwise inoperable, will permit the filters to be removed through the opening 30. A simple means for checking the operating of each of the filters and replacing them, is thus provided.

What is claimed is:

1. A machine having a liquid reservoir and a liquid pump disposed above said reservoir, a liquid container unit connected with said machine and having a portion thereof disposed within said reservoir and a portion thereof including a top wall disposed exteriorly of said machine, said container having an opening adjacent the bottom thereof disposed within said reservoir, establishing liquid communication between the reservoir and the container, said container having a manifold within the portion thereof disposed in said reservoir provided with at least one opening connectable to said pump, conduit means connecting said manifold opening to said pump, said manifold having at least one opening disposed below the liquid level in said reservoir and container for connection to a filter disposed in said container, a filter connected with said manifold opening and projecting therefrom

into the portion of said container disposed exteriorly of said machine, said exteriorly disposed container top wall including an openable cover disposed above the liquid level within said container to permit removal, installation and inspection of said filter within said container, whereby a filter may be easily removed and inspected.

2. A machine having wall portions forming a liquid reservoir, a liquid pump disposed above the liquid level in said reservoir, one of said wall portions having an opening therein, a liquid container unit having a portion thereof extending through said opening into said reservoir and a portion thereof disposed exteriorly of said opening and said machine, means connecting said container unit to said machine wall portion, the portion of said container disposed within said machine reservoir having an opening therein adjacent the bottom thereof establishing liquid communication between the reservoir and the container, said container having a manifold in the interiorly disposed portion thereof provided with at least one opening connectable to said pump and at least one opening for the reception of a filter disposed within said container, the exteriorly disposed portion of said container having an opening therein disposed adjacent the top thereof and above the liquid level in said container, and cover means for closing said opening and movable relative thereto to permit easy removal, installation and inspection of a filter disposed within said container and connected with said manifold opening.
